HARRY SLATER, OF METHUEN, MASSACHUSETTS.

SPINDLE-WHIRL LOCK.

1,369,907.

Specification of Letters Patent.

Patented Mar. 1, 1921.

Application filed June 30, 1920. Serial No. 393,012.

To all whom it may concern:

Be it known that I, HARRY SLATER, a citizen of Great Britain, residing at Methuen, in the county of Essex and State of 5 Massachusetts, have invented certain new and useful Improvements in Spindle-Whirl Locks, of which the following is a specification.

This invention relates to whirl locks for 10 cap spinning frames such as are used particularly for spinning worsted yarn.

In such frames, there are a plurality of fixed or dead spindles, each of which carries at the top a cap. Each of these spindles 15 passes through the lifter plate, and each carries a bobbin tube, which carries a bobbin and has fixed at the bottom a whirl. The lifter plate raises and lowers the whirl, the tube, and the bobbin as the yarn is built 20 up. Between the bottom of the tube or whirl and the lifter plate, there is generally an annular friction washer, and at the top of the whirl is a tooth which engages a slot 25 from the bobbin to insure that the bobbin will revolve.

In such frames there is generally a fly board, in sections, containing perhaps eight eyes, directly over the caps, and when removing a single cap and bobbin for doffing, 30 or otherwise, if the bobbin sticks to the tube, as frequently happens, both the tube and whirl, and also the friction washer, are removed with the bobbin. In such case, the friction washer often drops on the ground 35 and its recovery causes delay. The operative should seize the whirl with the right hand and hold it down while he frees the bobbin with the left hand. In so doing, often the hand with the bobbin comes up 40 sharply, striking the fly board and breaking six or eight ends.

I am aware that various devices have been used for locking spindles and whirls in position, but my device can be instantly attached to an old cap spinning frame without boring holes, filing, or otherwise touching it, and can be instantly removed. By its use the operative can remove the cap and bobbin with the left hand, and put on 45 an empty bobbin with the right hand, thus saving time.

In the drawings, Figure 1 is an elevation partly in section of a spindle, bobbin, whirl, cap, fly board, and lifter plate of a worsted 50 cap spinning frame, showing the whirl and

friction washer raised and my lock in its first position as it is placed on the plate.

Fig. 2 is a section looking down on the line 2—2 of Fig. 1.

Fig. 3 is a sectional view similar to Fig. 60 2 showing my lock in position.

Fig. 4 is an elevation partly in section from the right of Fig. 3.

Fig. 5 is an elevation partly in section similar to Fig. 4, showing how the friction 65 washer can be omitted.

Fig. 6 is a sectional view taken below the whirl showing a modification of my lock in position.

Fig. 7 is a sectional view from the right 70 on line 7—7 of Fig. 6.

In the drawings, A represents part of a cap spinning frame, B is a fly board attached thereto by hinges such as 10 and having guide eyes such as 11. S shows a dead 75 spindle attached at the bottom 13 to another part of the frame A in a well known manner which it is not necessary to show. The cap C is carried by the top 12 of spindle S and serves to guide the roving R on 80 to the bobbin G in a well known manner. L is the lifter plate, K is a friction washer which rests thereon and has an axis which substantially coincides with that of spindle S. F is a bobbin tube adapted to revolve 85 on spindle S having at the bottom a whirl W which comprises the base 20, flanges 21 and 22, and a pulley section 23 between the flanges to receive the driving band. At the top, the whirl has teeth 24 which fit into 90 a slot 14 in the bottom of a bobbin G which is slipped over bobbin tube F in a well known manner. All the above parts are old and well known.

My whirl lock H comprises a flat base 95 30 adapted to rest on lifter plate L and has a slot 31 of a size to pass by the spindle S from the position shown in Fig. 2 to that shown in Fig. 3. It also has an annular groove 32, the axis of which, when in position, coincides with the spindle axis and is preferably adapted to receive the friction washer K or another similar washer in place thereof which serves as an annular bolt member slidable on the spindle to fit into 100 105 annular groove 32.

Extending upwardly from base 30, clearing the lower flange 22, is the upwardly extending stop finger 33 which extends in at 34 so that, when in position, the lower flange 110

22 of the whirl W will strike it if it is attempted to remove the bobbin tube with the whirl. Extending downward from base 30 is a foot 35 having a toe 36 which extends under lifter plate L, as clearly shown in Fig. 4.

As shown in Fig. 5, the base 20 of the whirl W may be made of such a size as to fit into annular groove 32 in lock H, thus 10 serving as an annular bolt member slidable on the spindle to hold the lock in position.

The annular groove 32, and either washer K or said base 20, may be considered means to hold the whirl lock in position.

15 As shown in Figs. 6 and 7, the lock M may have the finger 33 and foot 34, while the base 40 may have a slot 41 at the back instead of at the side, and instead of an annular groove may have an annular upwardly 20 projecting neck 42 which is also open at the back to coincide with slot 41.

In this case the friction washer or annular bolt member 43 slips down over neck 42, these two serving as means to hold the 25 whirl lock in position.

Neck 42 or groove 32 may be regarded as an annular locking member, and base 20, washers K or 43 as annular bolt members.

I prefer the slot in the right or left rather 30 than the back side because the washer sometimes lifts with the whirl and the lock is more easily shaken out of position when the slot is at the back. I prefer a steel or boxwood annular bolt member to reduce friction 35 and to take the wear, rather than the base of the whirl.

To put the lock H in position, it is slipped on the rail as shown in Fig. 1, the washer and whirl are lifted until the end 34 of 40 stop finger 33 is between flanges 21 and 22, lock H is slipped up to spindle S and the washer or base is dropped into the annular groove. It is removed in the reverse manner.

45 I claim:

1. The combination in a cap spinning frame having a lifter plate, a spindle and a bobbin tube having a whirl slidable on said

spindle, of a whirl lock comprising a flat base adapted to rest on the lifter plate having a slot of a size to pass by the spindle and an annular groove in the top, the axis of which coincides with the spindle axis, a stop finger extending upward and inward to a point over part of the whirl, and a foot 55 which extends down and under the lifter plate, with an annular bolt member slidable on the spindle to fit into said annular groove.

2. The combination in a cap spinning frame having a lifter plate, a spindle and 60 a bobbin tube having a whirl slidable on said spindle, of a whirl lock comprising a flat base adapted to rest on the lifter plate and having a slot of a size to pass by the spindle, a stop finger extending upward and inward over a part of the whirl, a foot which extends down and under the lifter plate, and an annular locking member with an axis which coincides with the spindle axis, with an annular bolt member slidable on the spindle adapted to engage the annular locking member to hold the whirl lock in position.

3. The combination in a cap spinning frame having a lifter plate, a spindle and a bobbin tube having a whirl slidable on said 75 spindle, of a whirl lock comprising a flat base adapted to rest on the lifter plate and having a slot of a size to pass by the spindle, a stop finger extending upward and inward over a part of the whirl and a foot which 80 extends down and under the rail, with means to hold the whirl lock in position.

4. The combination in a cap spinning frame having a lifter plate, a spindle and a 85 whirl slidable on said spindle, of a whirl lock comprising a flat base adapted to rest on the lifter plate and having a slot of a size to pass by the spindle, a stop finger extending upward and inward over a part of the whirl and a foot which 90 extends down and under the rail, with means to hold the whirl lock in position.

In testimony whereof I have affixed my signature.

HARRY SLATER.
